UNITED STATES PATENT OFFICE.

JAMES M. TAYLOR, OF SAN FRANCISCO, CALIFORNIA.

CONTAINER-FORMING MACHINE.

1,077,496.

Specification of Letters Patent.

Patented Nov. 4, 1913.

Application filed April 5, 1912. Serial No. 888,696.

To all whom it may concern:

Be it known that I, JAMES M. TAYLOR, a citizen of the United States, residing in the city and county of San Francisco and State 5 of California, have invented certain new and useful Improvements in Container-Forming Machines, of which the following is a specification.

The present invention relates to an im- 10 proved receptacle or paper container making machine, and particularly to that type of machine for forming containing vessels from card board or other fibrous material for dispensing liquids or other substances where 15 a sanitary receptacle is required.

The principal object of the invention is to provide a machine into which suitably shaped blanks of material, preferably sheets of paraffin coated paper or card board, are au- 20 tomatically fed in succession to an adhesive applying mechanism, then formed into semi-cylindrical or substantially U-shaped bodies which are passed onto mandrels and folded into hollow cylindrical bodies; then while 25 carried by said mandrels securing a bottom in each body, and finally after the adhesive has fully dried at the edges of the container 30 seams, ejecting the completed article from the mandrel.

A further object of the invention is to render automatically the work of forming containers and applying bottoms thereto, and by doing so materially increasing the output of a container making plant and 35 correspondingly reducing the cost of making said containers.

The invention comprises a feed table for receiving the blanks, means for applying an adhesive to one edge of the blank while it 40 is being carried forward by said feed table, mechanism for forming said blanks into semi-cylindrical or substantially U-shaped bodies, means for removing said semi-cylindrical or substantially U-shaped bodies from 45 said formers onto suitable mandrels carried by a rotatable wheel, clamping arms surrounding said mandrels, and devices for closing said arms around said blanks carried by said mandrels, a bottom applying station, 50 means for rotating said wheel carrying said blanks from the feed table to the bottom applying station, mechanism for applying a bottom to said blanks, and devices at a distant point of travel of said wheel for opening 55 said clamping arms and ejecting said completely formed container from said mandrel.

With the above mentioned and other objects in view, the invention consists in the construction and novel combination of parts hereinafter fully described, illustrated in 60 the accompanying sheets of drawings, forming a part of this invention, and pointed out in the claims hereto appended; it being understood that various changes in the form, proportion, size and minor details of construction within the scope of the claims here- 65 to appended may be resorted to without departing from the spirit or sacrificing any of the advantages of the invention.

To comprehend the invention, reference 70 should be had to the accompanying sheets of drawings illustrating a complete constructed apparatus for successively carrying out the invention, wherein—

Figure 1 is a front elevation of the ma- 75 chine with the supporting wheel carrying the mandrels and the clamping arms partly broken away, disclosing certain of the clamping arms in their open position away from the mandrel before the mandrel is 80 supplied with a blank, the feed table, the bottom applying station, the arms clamped tightly around the mandrels after the same have been supplied with blanks, and the mechanism for operating the respective 85 parts of the machine, the direction of travel of the mandrel supporting wheel being shown by the arrow. Fig. 2 is a top plan view of the machine, disclosing a portion of the mandrel supporting wheel, the bearing 90 for supporting the same, the feed table for the blanks, the adhesive applying mechanism, the means for forming the blank into a substantially U-shaped structure, the mechanism for positioning the blank onto 95 the mandrel, the bottom applying station, the operating mechanism for the respective parts of the machine, and the compressed air mechanism for discharging the formed containers from the mandrels. Fig. 3 is a 100 side elevation of the machine taken in the direction of the arrow in Fig. 1, disclosing the supporting wheel for carrying the mandrels, the clamping arms, the supporting and operating means therefor, the operating 105 mechanism for the feed table, the bottom applying station, the mechanism for coating the bottoms with an adhesive, the operating mechanism therefor, the mechanism for transmitting power from a drive wheel to 110 the operating shaft, and the gearing for intermittently rotating the supporting wheel

carrying the mandrels. Fig. 4 is a top plan detail view of the feed table disclosing the reciprocating feed plate, the worm for applying an adhesive to one edge of the blank 5 as it is being fed forward, the former around which the blanks are bent into a substantially U-shape, the plunger for removing the blank from the former onto the mandrel, and a portion of the mechanism 10 for operating the several parts. Fig. 5 is a sectional view of the feed table taken on line 5—5, Fig. 4, disclosing the reciprocating feed plate, the adhesive containing receptacle, the former around which the 15 blanks are bent, the reciprocating curved plate for bending the blanks around the former, the plunger for removing the bent blanks from the former, and the various cams and gears for operating the respective 20 members. Fig. 6 is an enlarged sectional view taken on line 6—6, Fig. 4, disclosing the former around which the blanks are bent, the reciprocating curved plate for bending the blanks around the former, the 25 plunger for removing the bent blanks from the former, the lugs carried by the plunger and projecting through the sides of the former into slots in the curved plate, the lugs being in a position to remove a bent 30 blank from the former. Fig. 7 is an enlarged detail sectional view of the former, the plunger mounted within the same, the curved plate in its lowermost position, and a blank in position to be bent around said 35 former. Fig. 8 is an enlarged detail sectional view of the former, the plunger mounted within the same, the curved plate in its uppermost position, and in the operation of bending the blank around said 40 former. Fig. 9 is a rear elevation of the mechanism for applying the bottom, disclosing the operating means therefor, the feed chute for the bottoms, the pivotally mounted adhesive receptacle, the rotary adhesive applying disk therein, the fingers for holding the bottoms before the plunger, and the mechanism for intermittently 45 throwing the adhesive applying disk in contact with the flanged edges of the receptacle bottom. Fig. 10 is a side elevation of the mechanism for applying the bottom with the plunger casing partly broken away, disclosing the plunger, the mechanism for reciprocating the same, a bottom carried by 50 the outer end thereof, the adhesive containing receptacle and the disk rotatably mounted therein, the mechanism for operating the same, and the mechanism for intermittently throwing the adhesive applying disk in contact 55 with the flanged edges of the receptacle bottom. Fig. 11 is an enlarged top plan view of one of the mandrels and the parts associated therewith in the position of expelling a completely formed container 60 therefrom, disclosing the cone-shaped man- 65

drel partly broken away, the presser arms in their open position, the ejector rod in its forwardly projected position and in alignment with the compressed air connections. Fig. 12 is a side elevation of Fig. 11 with 70 the clamping arms in a position to clamp a blank around the mandrel, disclosing the lower hinged clamping plate and the actuating cam and lever therefor, the side clamping arms and the actuating means therefor, 75 and the manner of attaching the structure to the supporting wheel. Fig. 13 is a front elevation, in detail, of the pivoted cam actuated dog for closing the lower clamp jaw, in the operation of closing the same, and the vertically movable cam actuated arm for engaging the mechanism for closing the side arms after a blank has been positioned on the mandrel. Fig. 14 is a front elevation in detail, with the supporting wheel in outline and the several clamping arms and the mandrel removed therefrom, disclosing the mechanism carried on the rear face of the supporting wheel of two of the container forming mandrels, and the clamping arms, 80 the lower jaw closing mechanism of the advanced one of the container formers being in a closed position and the side clamping arms of the same former having just been closed, and the lower jaw closing mechanism 85 of the lowermost container former just about to be engaged by the closing mechanism therefor. Fig. 15 is a front elevation of one of the container forming mandrels, disclosing the side clamping arms and the 90 lower clamping jaw, and with a blank surrounding the mandrel and about to be tightly clamped around the same, by the side clamping arms and the bottom in place. Fig. 16 is a view similar to Fig. 15, 95 but disclosing one of the side clamping arms in the position of clamping one side of the blank around the mandrel with the adhesively coated edge thereof upwardly, and the other side clamping arm about to 100 tightly stretch the other edge of the blank around the mandrel and clamp the edges thereof together, with bottom in place. Fig. 17 is a longitudinal sectional view of the bottom seating plunger, disclosing the 105 rotatable head thereof and the manner of mounting the same on the outer end of the plunger, and the split ring for forcing the peripheral flanged edges of the bottom into engagement with the side walls of the container. 110

In the detailed description of the machine, the term "front" refers to that part of the machine adjacent the blank feed mechanism and in front of the mandrel supporting 115 wheel, and the term "rear" refers to that part of the machine in rear of the mandrel supporting wheel.

In the drawings, referring more particularly to Figs. 1, 2 and 3, the reference nu- 120

meral 1 designates a suitable base plate provided at the front and rear ends thereof with suitable standards 2 and 3, in which are journaled the opposite ends of a drive shaft 4, the end of the shaft adjacent the standard 3 being provided with a suitable gear 5 intermeshing with a gear 6 mounted on a power shaft 7, adapted to be operated from any suitable source of power.

Extending upwardly from the rear of the base plate 1 and positioned adjacent the standard 3, is a supporting standard 8, provided at its upper end with a rectangularly projecting bearing shaft 9, which provides a supporting axis for the center of a wheel 10, which carries on its front face the container forming mandrels, the wheel being provided on its peripheral edge with suitable gear teeth 11 which intermesh with suitable teeth on a gear 13 which is mounted on a rotatable driven shaft 14. The shaft 14 is intermittently rotated by a suitable roll 15 carried by the drive shaft 4, the roll moving into and out of engagement with the radial slots 16 of the disk 17 secured to the shaft 14, whereby there is given to the said shaft 14 a step by step rotation by the described Geneva gear mechanism, and the same step by step movement is transmitted to the wheel 10 through the gear 13 and teeth 11.

A table 18 for feeding the blanks is provided at the front of the base plate 1, it being supported at its front end on the upper end of the standard 2 and at its rear by the support 19; the rear edge of the table terminating adjacent the front end of the hereinafter described forming mandrels carried by the wheel 10.

The blanks from which the articles or containers are to be formed, are placed on the feed table 18 between the outwardly flaring faces of the arms 20 and 20' projecting from the rear of a reciprocating feed plate 21 mounted to slide in parallel grooves or slots 22 in the top of the feed table 18. A reciprocating movement is imparted to the feed plate 21 through a rack 22' projecting from the under side of the plate, through a suitable slot 23 in the table, the rack intermeshing with a segment 24 mounted on one end of a shaft 25, supported by a bracket 26 to the underside of the feed table. The other end of the shaft 25 is provided with a pinion 27 which intermeshes with a rack 28 projecting from the upper surface of a yoke 29 straddling the drive shaft 4, the yoke being provided with a cam wheel 30 which fits in a cam groove 31 formed in the face of a wheel 32, keyed to rotate with the shaft 4.

As the blank is fed forwardly by the feed plate, the edge of the blank adjacent the arm 20' is coated on its under surface with a thin film of adhesive by any suitable

adhesive applying mechanism, preferably comprising an adhesive applying spiral 32' supported by a suitable shaft 33 and projecting through an opening 34 in the feed table 18, the ends of the shaft being journaled in bearings in either side of an adhesive receptacle 35 detachably secured to the underside of the feed table as by a clamp arm 36. The shaft 33 is provided exteriorly of the adhesive receptacle with a suitable toothed gear 37 which projects through a suitable opening in the feed table 18, the gear 37 intermeshing with a rack 38 carried by the underside of the arm 21' near the outer edge thereof.

From the above construction it will be observed that as the plate 21 with the blank between the arms thereof is forced rearwardly the rack 38 will rotate the adhesive applying spiral and the spiral is timed to operate and so constructed as to present a freshly coated edge thereof to the edge of the blank as it is advanced toward the former.

The blank is fed forward to a point adjacent the rear edge of the feed plate 18 and lies directly under a hollow cylindrical former 39 supported slightly above the table, and extending longitudinally of the center thereof, with its rear edge terminating flush with the rear edge of the table 18; the former being supported by an arm 40 projecting upwardly from one side of the feed table 18 and overhanging the working bed thereof.

As the blank is positioned under the former it is engaged from the underside by a reciprocating folding arm 41 substantially U-shaped in cross section, and forced around the former 39 until it assumes a semi-cylindrical or substantially U-shaped structure, as disclosed in Figs. 6, 7 and 8 of the drawings. The folding arm 41 is formed with a substantially U-shaped upper surface, the concavity of which is slightly larger than the diameter of the former 39 to permit the reception of the blank between the surfaces thereof, and is mounted to reciprocate through a suitable opening 39' in the feed table 18, directly below the former 39; the folding arm in its movement being guided by suitable lugs or guides 42, which project laterally from each side of said arm, and extend downwardly from the under surface thereof, the lugs being slidably mounted in vertical tracks or grooves 43 formed in brackets 44 secured to the underside of the feed table at each side of the opening 39'. A reciprocatory movement is imparted to the folding arm 41 by a link 45 pivoted to the underside thereof, as at 46, the lower end of said link being formed with an oval opening or cut out 47 therein, the side edges thereof straddling the shaft 4, an idler wheel 48 being mounted on the

link between its pivotal point and the oval opening therein and operated in a cam groove 49 in a wheel 50 keyed to rotate with the shaft 4.

- 5 After the sides of the blank are curved upwardly, the whole forming a semi-cylindrical or substantially U-shaped structure and the curved folding arm 41 is in its elevated position partly surrounding the former 39, the blank is engaged in its front edges and pushed rearwardly off of the former 39 onto a mandrel 51, mounted on the forward face of the supporting wheel 10, by a pair of oppositely disposed lugs 52
- 10 secured to the rear end of an oblong cylindrical plunger 53, mounted to reciprocate in a suitable opening extending longitudinally through the center of the former 39, the lugs 52 projecting through longitudinally extending slots 54 arranged one in either side of the former 39, the lugs also projecting into horizontally disposed guide ways 55 arranged one in either side of the inner surface of the folding arm 41 adjacent the upper edges thereof. A reciprocating movement is imparted to the plunger 53 through a rack 56 formed longitudinally of the upper surface thereof, the rack intermeshing with a segment 57 secured to the inner end
- 15 of a shaft 58 and projecting through a suitable cut out in the upper surface of the former 39, the shaft being rotatably mounted in a housing 59 extending longitudinally of the upper edge of the arm 40, the outer end
- 20 of the shaft carrying a segment 60 which intermeshes with a rack 62 formed in one face of a reciprocating arm 63, the arm receiving its movement through a lever 64 pivoted as at 65 to a suitable support 65',
- 25 and carrying at its inner end a roller 66 which operates in a cam groove 67 of the disk 68 which is mounted to rotate with the shaft 4. The arm 63 is mounted in a suitable guide way 69 formed at the outer end
- 30 of the arm 40 and is connected at its lower end to the outer end of the lever 64 by an adjustable link 70.

The timing and operation of the respective parts is such that as each blank is pushed rearwardly from the former, a forming mandrel is in position to receive the same.

The mandrels 51 around which the containers are formed and the clamping arms associated therewith are supported in spaced relation to each other on the forward face of the supporting wheel 10 adjacent the peripheral edge thereof; and each mandrel and its associated parts being the same, it is not thought necessary to describe each one separately, but a description of one is thought will suffice.

Each mandrel 51 is in the form of a hollow cylinder closed at its outer end as at 51' and tapering as the frustum of a cone and

is mounted at right angles to the front face 65 of the wheel 10 with its tapered end outwardly and the enlarged end secured in any suitable manner to the face of the supporting wheel 10. In the outer end of the mandrel is formed a circular depression 72, 70 which provides a seat for a disk shaped expelling plunger head 73, which is provided with a supporting shaft 74 in which is formed a longitudinal bore 76, the shaft 74 extending longitudinally of the center of the mandrel, through a suitable opening in the wheel and projects a short distance in the rear thereof, the plunger head being normally retained in its seat by the action of a spring 75 coiled around the rear thereof. 80

Mounted on the supporting wheel 10 in spaced relation below the mandrel 51 and arranged angularly thereto is a supporting bracket 76', the outer end of which is curved upwardly in spaced relation to the supporting wheel 10 and is provided with spaced bores which form a bearing for the inner ends of rotatably mounted stub shafts 77 and 78, which extend respectively through corresponding bores in the lower ends of supporting lugs 79 and 80 extending respectively from the lower edges of semi-cylindrical clamping arms 81 and 82, adjacent the forward ends thereof, as disclosed in Figs. 12, 15 and 16 of the drawings. The 90 clamping arms 81 and 82 extend longitudinally of the mandrel, one on either side thereof, and the curved inner faces thereof are of substantially the same curvature as the contour of the mandrel 51, and when 100 said arms 81 and 82 are clamped around the mandrel, in a hereinafter described manner, the upper edges thereof are in substantially meeting relation and the lower edges are spaced apart, the space therebetween being 105 filled by a lower clamping jaw 83, hinged at its rear end as at 84 to the supporting wheel 10 and operated in a hereinafter described manner. The side clamping arms 81 and 82 and the bottom clamping jaw 83 110 project slightly beyond the end of the mandrel 51, as in Figs. 11 and 12 of the drawings. The lower clamping jaw 83 is forced against the mandrel 51 by the action of a shaft 85, extending through the supporting wheel 10 and carrying at its forward end a cam 86 adapted to be rotated by the shaft into engagement with an outwardly projecting lug 87 on the under surface of the jaw 83. The shaft 85 carries on 115 its rear end a suitable arm 88 having an enlarged portion 89 at one end thereof, which, when the wheel 10 is rotated contacts with the upper end of a dog 90 pivotally mounted as at 91 to a suitable support 92 projecting 120 from the upper end of the support 3, the dog adapted to be actuated by a cam block 93 mounted on the shaft 4 and which con-

tacts with an antifriction roller 94 on the lower end of the dog.

Loosely surrounding the shaft 85 between the cam 86 and the arm 88 and rotatably mounted in an opening in the wheel 10 is a sleeve 95 the forward end of which is secured in a bore in the supporting lug 96 projecting from the lower edge of the clamping arm 81 near the inner end thereof, and to the rear of said sleeve is secured a toothed segment 97 which intermeshes with a corresponding segment 98 on the inner end of a shaft 99 positioned adjacent the sleeve 95 and rotatably mounted in the wheel 10, the forward end of said shaft 99 being mounted in a supporting lug projecting from the lower edge of the clamping arm 82 near the inner end thereof. An arm 101 extends laterally from a portion of the edge of the segment 98 and is pivotally connected as at 102 to one end of a link 103, the other end of said link being pivotally connected as at 104 to the end of an arm 105 projecting from a hub 106 pivotally mounted about a stud 107 secured to the wheel 10. At the end of the link 103 adjacent the pivot point 104 is formed a finger 108, which, when the parts are operated in a hereinafter described manner and the arms 81 and 82 are closed, is adapted to contact with a flattened seat 109 formed in the hub 106 and provide a lock for the arms as disclosed in Figs. 13 and 14 of the drawings.

The segments 97 and 98 are so arranged that when the clamping arms are closed around the blank as it is supported by the mandrel, the arm 82 will close first, forcing that portion of the blank carrying the adhesive around the mandrel with the adhesive side upwardly, and then the clamping arm 81 will be closed, bringing the other portion of the blank over, and after drawing the blank tightly around the mandrel forcing the top edge against the adhesive on the under edge, and securing the two edges together.

The machine is timed to operate in such a manner that after the blank in its substantially U-shape form is fed to the mandrel and the plunger 53 is drawn back to the position in Fig. 5, the wheel 10 will be rotated by the elements of the Geneva gearing coming into operation, and while the wheel is in its movement, the arm 88 in its path of movement will be engaged by the dog 90 and the cam 86 associated with said arm through the shaft 85, will be operated, forcing the lower clamping jaw 83 upwardly and clamping the blank to the mandrel. When this operation is completed the Geneva gearing will be in its inoperative relation and the mandrel carrying the semiformed container blank will be at a point of rest before bottom ap-

plying station which inserts a bottom in the 65 semiformed container and operates in the following manner:—Secured to the feed table 18 at the opposite side thereof from the arm 40, is an upstanding bracket 110 provided at its top with an enlarged bore 70 111 through which reciprocates a suitable cylindrical plunger 112, to the outer end of which is rotatably mounted a plunger head 112', it being attached by a headed bolt 112''. Extending circumferentially of the 75 outer end of the rotatable plunger head 112' is a split ring 112³ formed respectively with rectangular front and peripheral edges 112⁴ and 112⁵ and a beveled inner edge 112⁷ which contacts with a suitable bevel on the 80 rotatably mounted head 112'. The ring 112³ when in its normal position on the rotatable head is of the same diameter as the inside diameter of the flanges of the bottoms to be applied. Extending from 85 the rear of the plunger is an adjustable link 113 pivoted as at 114 to the upper end of a lever 115 extending upwardly through an opening in the feed table and pivoted below the table 18 as at 116 to a bracket 90 117, secured to the underside of the table; the lever being provided at its lower end with a suitable idler roller 118 adapted to operate in a cam groove 119 cut in the periphery of a cam wheel 120, keyed to rotate 95 with the shaft 4.

The bottoms to be applied to the receptacle are fed to the applying plunger in a formed condition, *i. e.* with a flat face and a flanged periphery; through a downwardly inclined trough or chute, formed of parallel spaced angle rods 121 and 121', the lower ends of which are supported by the bracket 110, at right angles to the outer flat face of the plunger, and terminate short 105 of the front of the enlarged bore 111.

The bottoms are positioned in front of the plunger head by a pair of fingers 122 and 123, pivoted respectively as at 124 and 125 to the upper and lower guides or members 121 and 121' of the chute, the fingers being connected together by a transverse rod 126, the ends of which are pivoted to the fingers as at 127 and 128. The finger 123 is pivotally connected at a point in advance of its pivotal point 125, by a rod 129, to the upper edge of an oblong adhesive containing receptacle 130, which is pivotally mounted at its rear end as at 131 to the bracket 110, the front end of the receptacle terminating below the finger 123.

Rotatably mounted in the adhesive receptacle near the forward end thereof, on a shaft 131' journaled in either side of the receptacle, is an adhesive applying disk 125 132 which is rotated by an endless drive chain 133, extending around a toothed drive wheel 134 keyed to the shaft 4, and around

a suitable toothed gear 135 carried by the shaft 131 exteriorly of the receptacle.

The adhesive containing receptacle 131 is pivotally connected at its underside near the forward end thereof to an adjustable rod 136, the lower end of which is pivotally connected to one end of a lever 137 pivotally supported as at 138 to a bracket on the standard 19, the opposite end of 13 said lever being provided with an idler roller which contacts with, and is operated by the peripheral surface of a cam roller 139 keyed to rotate with the shaft 4 and positioned adjacent the toothed wheel 134. 15 The chain 133 contacts with a stationary idler 140 rotatably mounted in the feed table 18 and with an idler 141 under suitable spring tension, the idlers maintaining the chain taut at all times. 20 From the above description it will be readily seen that when the cam member on the roller 139 contacts with the lever 137, the adhesive applying disk 132, which is rotated in the direction of the arrow—Fig. 25 9—will be forced against the peripheral flange of the bottom, as it is carried by the forward end of the plunger head and retained between the fingers 122 and 123, and will rotate the bottom and the 30 rotary plunger head 112, coating the entire circumference of the flange with adhesive, at which time the cam member on the roller 139 will have passed its point of contact with the lever 137, permitting the forward end of the adhesive receptacle 130 to drop, which being connected by the rods 129 and 126 with the fingers 122 and 123 will cause the same to open 35 outwardly away from the periphery of the bottom, and permit the plunger 112 to move therebetween and to apply the bottom to the semi-formed receptacle.

A short interval before the bottom is applied to the receptacle in the above described manner, the pivot 104, connecting the link 103 and the arm 105 and which projects slightly outwardly from the link will be engaged by a spring finger 142 carried at the upper end of the arm 143 operated in a hereinafter described manner, and forced upwardly partly closing the clamping arms 81 and 82 around the blank forming the same into a substantially cylindrical body but not forcing the upper edges of 55 the arms 81 and 82 into meeting relation or the finger 108 against the seat 109. The lower end of the arm 143 is pivoted as at 144 to a supporting rod 145 which is mounted to reciprocate vertically in a guide way 60 146 formed at the extreme upper end of the standard 3, the supporting rod 145 being provided at its lower end with an idler roller 147 which contacts with the peripheral edge of a cam 148 keyed to rotate with 65 the shaft 4. To permit the arm 143 to

follow the pivotal point 104 a short distance after the finger 142 has engaged the same and to limit the lateral movement of said arm, the arm 143 is provided midway of its length with an arcuate slot 149 through which projects a stud 150, carried by the upper end of the supporting rod 145. 70

When the clamping arms 81 and 82 are partly closed around the blank, as previously stated, the cam 148 is in a position of its rotation with the edge A thereof contacting with the roller 147, and when in this position the bottom is forced in the substantially cylindrical body by the timed actuation of the lever 115 by the cam groove 80 119. The peripheral edges of the bottom are forced against the sides of the container by the action of the split ring 112³ as the flat face of the bottom contacts with the mandrel head 73. After the bottom is placed in the container the cam 148 in its movement of rotation will, through its associated parts clamp the arms 81 and 82 tightly around the blank and lock the finger 108 in its seat 109. The action of the clamping arms 81 and 82 is such that as they are closed around the blank the same is drawn tightly around the mandrel, the overlapped edges thereof are clamped one on the other and the bottom is tightly clamped in place. 90 95

The above operations take place successively as each mandrel is positioned before the blank feeding and bottom applying stations, and as the wheel 10 has about completed its revolution the spring arms 151 and 152 carried by the upright 8 to engage respectively the projecting pivot 104 and an arm 89¹ projecting upwardly from the arm 88, and as the wheel 10 continues to revolve open the side clamping arms 81 and 82 and drop the lower jaw 83. The wheel 10 in its movement forces the shaft 74 into contact with the incline 153 of an ejector block 154, supported on the member 8, the plunger head 73 of the shaft forcing the container longitudinally of the mandrel, until the longitudinal bore 76 in the shaft aligns with a compressed air blast 155, at which time the completely formed container will be blown from the mandrel. The air 110 is compressed by a suitable pump 156 operated by the shaft 7 and forced into a receiver 157 which is connected through a suitable pipe 158 to the aperture 155, a rotary valve 159 is mounted in the pipe 158 and is provided with an operating head 115 formed of a plurality of outwardly projecting fingers 160 which are adapted to be engaged by outwardly projecting pins 161 arranged in spaced relation on the wheel 5. 120 The pins are timed to contact with the fingers and open the valve 159 at a time when a bore 76 of a supporting rod 74 is in alignment with an aperture 155. 125

A band wheel 160¹ is loosely mounted on 130

the shaft 7, and is adapted to receive a belt or band extending from any suitable source of power, which power is transmitted to the shaft 7 by a clutch 161 keyed to rotate with the shaft 4. A suitable lever 162 extends from the clutch 161 to within easy reach of the machine operator, and by this lever the speed of the container making machine may be varied without varying the speed of the power source.

Having thus described the invention what is claimed as new and desired to be protected by Letters Patent is:—

1. In a receptacle or container forming machine, the combination with means for feeding blanks thereto, devices for forming said blanks into semi-cylindrical bodies, means for forming said semi-cylindrical bodies into tubular containers having a side seam, and devices for inserting bottoms within said tubular containers when in a semi-formed condition and before the side seams thereof are completely closed.

2. In a receptacle or container forming machine, the combination with means for feeding blanks thereto, devices for forming said blanks into semi-cylindrical bodies, means for forming said semi-cylindrical bodies into tubular containers having a side seam and lapping the edges thereof, and devices for inserting bottoms within said tubular containers when in a semi-formed condition and before the edges thereof are lapped.

3. In a receptacle or container forming machine, the combination with means for feeding the blanks thereto, devices for forming said blanks into semi-cylindrical bodies, means for forming said semi-cylindrical containers into tubular bodies and clamping the edges thereof together forming a side seam, devices for inserting bottoms within said tubular containers when in a semi-formed condition and before the edges thereof are clamped together, and means for expelling the formed containers with their applied bottoms from the machine.

4. In a receptacle or container forming machine, the combination with means for feeding blanks thereto, mechanism for applying an adhesive to one edge of the blanks, devices for forming said blanks into semi-cylindrical bodies, means for forming said semi-cylindrical bodies into tubular containers and securing the adhesive coated edge to the opposite edge of said blanks to form a side seam, devices for inserting bottoms within said tubular containers when in a semi-formed condition and before the edges thereof are secured together, and means for expelling the formed containers with their applied bottoms from the machine.

5. In a receptacle or container forming machine, the combination with the mandrel on which the body of the container is

formed; of mechanism for supplying a semi-cylindrical body blank to said mandrel, means for completely closing the semi-cylindrical body blank on the mandrel, mechanism for inserting a bottom within the formed body when in a semi-formed condition, and devices for expelling the formed container with its applied bottom from the mandrel.

6. In a receptacle or container forming machine, the combination with a mandrel on which the body of the container is formed, mechanism for supplying body blanks to said mandrel, means for closing the body around the mandrel, mechanism for inserting a bottom within the formed body when in a semi-formed condition and previous to the closure thereof, and devices carried by the mandrel for expelling the formed container with its applied bottom from the mandrel.

7. In a receptacle or container forming machine, the combination with a mandrel on which the body of the container is formed, mechanism for supplying body blanks to said mandrel, means for closing the body around the mandrel, mechanism for seating a bottom in the formed body, means associated with said bottom seating mechanism for supplying the bottom with an adhesive before it is seated in the formed body, and devices for expelling the formed container with its applied bottom from the mandrel.

8. In a receptacle or container forming machine, the combination with a supporting carrier, a plurality of container forming mandrels supported thereby, clamping devices surrounding each of said mandrels, mechanism for placing body blanks around said mandrels and bottoms upon the blanks, devices for closing the clamping devices around the mandrels to fold the blanks around the bottom, and devices for expelling the formed container with its applied bottom from the mandrel.

9. In a receptacle or container forming machine, the combination with a supporting carrier, container forming mandrels supported on said carrier, clamping devices surrounding each of said mandrels, mechanism for supplying body blanks to said mandrels, means for operating the clamping devices to close the body around the mandrel, mechanism for seating a bottom in the formed body surrounded by said clamping devices, means for operating the clamping devices to open the same from around the formed container, and devices for expelling the formed container with its applied bottom from the mandrel.

10. In a receptacle or container forming machine, the combination with a supporting carrier, mechanism for imparting an intermittent motion thereto, container forming mandrels supported by said carrier,

clamping devices surrounding each of said mandrels, mechanism for supplying body blanks to said mandrels, mechanism for applying an adhesive to one edge of the blank 5 as it is being fed to the mandrel, means for operating the clamping devices to close the body around the mandrel and securing the edges thereof together, mechanism for inserting a bottom within the formed body 10 while surrounded by said clamping devices, means for operating the clamping devices to open the same from around the formed container, and devices for expelling the formed container with its applied bottom from the 15 mandrel.

11. In a receptacle or container forming machine, the combination with a supporting wheel, container forming mandrels carried by said wheel, mechanism for supplying adhesively coated body blanks to said mandrels, clamping arms associated with each of said mandrels, means for operating said arms to tightly stretch the blank around the mandrel and lap the side edges thereof, 20 mechanism for inserting an adhesively coated bottom within the formed body, means for operating the clamping arms to open the same from around the formed container after the bottom is inserted therein, 25 and devices for expelling the formed container with its applied bottom from the mandrel.

12. In a receptacle or container forming machine, the combination with a rotary member, a plurality of formers mounted thereon, means for rotating said member intermittently, means for folding a glued blank around the former during one pause, means for inserting an adhesively coated 30 bottom within said formed blank when in a semiformed condition and during another pause, and means carried by the former and operated by the rotation of the rotary member for ejecting the formed container with 35 its applied bottom during another pause.

13. In a receptacle or container forming machine, the combination with a mandrel, means for feeding a blank thereto, a plurality of folding arms therefor arranged one 40 on each side, a lower clamping jaw, means for independently operating the lower clamping jaw to clamp the blank to the mandrel, means for simultaneously operating the folding arms one in advance of the other 45 to tightly stretch the blank around the mandrel and lap the side edges thereof, and means for inserting a bottom within said formed blank while on said mandrel and surrounded by said folding arms and clamp- 50 ing jaw.

14. In a receptacle or container forming machine, the combination with means for feeding blanks thereto, means for forming said blanks into tubular containers and

clamping the edges thereof together forming 65 a side seam, devices for inserting a bottom within said tubular body before the edges thereof are clamped together and when in a semi-formed condition, and means for expelling the formed container with its applied bottom from the machine. 70

15. In a receptacle or container forming machine, the combination with a mandrel, means for feeding a blank thereto, clamping means encircling said mandrel and comprising a plurality of hinged sections, means for first forcing the bottom section toward the mandrel to clamp the blank to the mandrel, and secondly closing the side sections 80 around the mandrel one in advance of the other to tightly stretch the blank around the mandrel and lap the side edges thereof, and means for inserting a bottom within said formed blank while on said mandrel and encircled by said clamping means. 85

16. In a receptacle or container forming machine, the combination with a mandrel, means for feeding a blank thereto, clamping means encircling said mandrel and comprising a plurality of hinged sections, means for first forcing the bottom section toward the mandrel to clamp the blank to the mandrel, and secondly closing the side sections 90 around the mandrel one in advance of the other to tightly stretch the blank around the 95 mandrel and lap the side edges thereof, means for inserting a bottom within said formed blank while on said mandrel and encircled by said clamping means, and means for expelling the formed container 100 with its applied bottom from the mandrel.

17. In a receptacle or container forming machine, the combination with a cone shaped mandrel, a cone shaped clamping 105 means shaped to conform thereto and comprising a plurality of hinged sections for encircling said mandrel, means for forcing the bottom section of the clamping means toward the mandrel to clamp a body blank 110 thereto, devices for closing the side sections thereof to form the blank around the mandrel and lap the side edges thereof, and means for inserting an adhesively coated bottom within the formed body while encircled by said clamping means. 115

18. In a receptacle or container forming machine, the combination with a cone shaped mandrel, a cone shaped clamping means shaped to conform thereto and comprising a plurality of hinged sections for encircling said mandrel, means for forcing the bottom section of the clamping means toward the mandrel to clamp a body blank thereto, devices for closing the side sections 120 thereof to form the blank around the mandrel and lap the side edges thereof, means for inserting an adhesively coated bottom

- within the formed body while encircled by said clamping means, and devices for expelling the formed container with its applied bottom from the mandrel.
- 5 19. In a receptacle or container forming machine, the combination with a cone shaped mandrel, a clamping means shaped to conform thereto and comprising a plurality of hinged sections for encircling said 10 mandrel, means for forcing the bottom section of the clamping means toward the mandrel to clamp a body blank thereto, devices for closing the side sections to form the blank around the mandrel and lap the side 15 edges thereof, means for inserting an adhesively coated bottom within the formed container while encircled by said clamping means and when in a semi-formed condition, a plunger mounted in the mandrel, and devices for operating said plunger to expel the 20 formed container with its applied bottom from the mandrel.
20. In a receptacle or container forming machine, the combination with mechanism 25 for receiving and forming a body blank into a tubular container having a side seam, and means for inserting a bottom into said container prior to closing the side seam thereof and when in a semi-formed condition.
- 30 21. In a receptacle or container forming machine, the combination with mechanism for receiving and forming a body blank into a tubular container having a side seam, means for positioning a bottom relative to the body 35 prior to a closure of its side seam, and devices for applying an adhesive to the bottom as fed toward the body forming mechanism.
22. In a receptacle or container forming 40 machine, the combination with mechanism for receiving and forming a body blank into a tubular container having a side seam, means for inserting a bottom into said container when in a semi-formed condition and 45 prior to closing the side seam thereof, and means for expelling a formed container with
- its applied bottom from within the body forming mechanism.
23. In a receptacle or container forming machine, the combination with mechanism 50 for receiving and forming a body blank into a tubular container, means for positioning a bottom relative to the body prior to the closure of its side seam, devices for applying an adhesive to the bottom as fed toward 55 the body forming mechanism, and means for expelling a formed container with its applied bottom from within the body forming mechanism.
24. In a receptacle or container forming 60 machine, the combination with mechanism for receiving and forming a body blank into a tubular container, devices for applying an adhesive to the blank as it is fed to the forming mechanism, means for positioning a bottom relative to the body prior 65 to the closure of its side seam and forcing the side edges of the bottom against the inner face of the body after the closure of its side seam, devices for applying an adhesive 70 to the bottom as fed toward the body forming mechanism, and means for expelling the formed container with its applied bottom from within the body forming mechanism. 75
25. In a receptacle or container forming machine, the combination with a mandrel for receiving and forming a body blank into a tubular container, means for forming said blank into a semi-cylindrical body before it 80 is fed to said mandrel, means for positioning a bottom relative to the body prior to the closure of its side seam, and means for expelling a formed container with its applied bottom from the mandrel. 85

In testimony whereof I have signed my name to this specification in the presence of two subscribing witnesses.
